UNITED STATES PATENT OFFICE

159,833

COMBINATION DRIP MOLDING AND MOUNTING BRACKET FOR AUTOMOBILE VISOR

William A. Maher, Detroit, Mich.

Application November 29, 1949, Serial No. 6,322

Term of patent 14 years

(Cl. D14—6)

To all whom it may concern:

Be it known that I, William A. Maher, a citizen of the United States of America, residing at Detroit, in the county of Wayne and State of Michigan, have invented a new, original, and ornamental Design for Combination Drip Molding and Mounting Bracket for Automobile Visor, of which the following is a specification, reference being had to the accompanying drawing, forming a part thereof, wherein:

Fig. 1 is a perspective view showing a combination drip molding and mounting bracket for automobile visor, embodying my new design, the dotted line showing of a fragmentary front portion of an automobile being for illustrative purposes only.

Fig. 2 is an outer edgewise elevational view of the bracket,

Fig. 3 is a top plan view thereof,
Fig. 4 is an inner edgewise elevational view of the same, and

Fig. 5 is a transverse sectional view taken on the line 5—5 of Fig. 3.

I claim:

The ornamental design for a combination drip molding and mounting bracket for automobile visor, substantially as shown and described.

WILLIAM A. MAHER.
